UNITED STATES PATENT OFFICE.

FREDERICK PIEBES, OF JERSEY CITY, NEW JERSEY.

DESIGN FOR A COLLAR AND CUFF.

SPECIFICATION forming part of Design No. 14,675, dated February 12, 1884.

Application filed December 1, 1883. Term of patent 3½ years.

To all whom it may concern:

Be it known that I, FREDERICK PIEBES, a citizen of the United States, residing at Jersey City, Hudson county, New Jersey, have 5 invented and produced a new and Original Design for Fluted or Ruffled Collars and Cuffs, of which the following is a specification, reference being had to the accompanying drawings, forming part thereof.

10 Figure 1 is a perspective view, partly in full and partly in outline, of my newly-designed ruffled collar; and Fig. 2 is a perspective view, partly in full and partly in outline, of the same, showing a modification.

15 The essential feature of my design consists of the angular outline of periphery *a*, with fluted sides *b* and the fluted inner surface, *c*, as seen in the perspective views of the drawings, wherein a collar is represented in part,

but so as to illustrate with sufficient clearness 20 the design of a complete collar. The drawings also represent as fully the design of the cuff, which is in all respects the same as the collar, only it will be proportionately smaller than the collar.

25

I claim—

1. The design for a collar or cuff herein shown and described, consisting of the angular outline of periphery *a*, with ruffled sides *b*.

2. The design for a collar or cuff herein 30 shown and described, consisting of the angular outline of periphery *a*, with ruffled sides *b* and the ruffled inner surface *c*.

FREDERICK PIEBES.
